DESIGN FOR AN AIRPLANE

Leo E. Oliver, Sanger, Calif.

Application December 23, 1940, Serial No. 97,563

Term of patent 14 years

To all whom it may concern:

Be it known that I, Leo E. Oliver, a citizen of the United States, residing at Sanger, in the county of Fresno and State of California, have invented a new, original, and ornamental Design for an Airplane of which the following is a specification, reference being had to the accompanying drawing, forming a part thereof.

Figure 1 is a top plan view of an airplane, showing my new design.

Figure 2 is a side elevational view of the same.
Figure 3 is a front end elevational view of the airplane.

Figure 4 is a longitudinal section on line 4—4 of Figure 1.

I claim:
The ornamental design for an airplane, as shown.

LEO E. OLIVER.
